STORAGE SHELF UNIT

Robert L. Propst, Ann Arbor, Mich., and Ronald H. Beckman, New York, N.Y., assignors to Herman Miller, Inc., Zeeland, Mich., a corporation of Michigan

Filed Nov. 27, 1964, Ser. No. 82,804

Term of patent 14 years

(Cl. D33—2)

FIG. 1 is a front perspective view of a storage shelf unit showing our design;

FIG. 2 is a rear perspective view;

FIG. 3 is an end elevational view taken from the right in FIG. 1;

FIG. 4 is a sectional view of one upright support column of the support pedestal, taken on plane IV—IV of FIG. 3;

FIG. 5 is a sectional view of a portion of the pedestal, taken on plane V—V of FIG. 3; and

FIG. 6 is a sectional view of another portion of the pedestal, taken on plane VI—VI of FIG. 3.

The dominant features of our design reside in those portions shown in full lines on the drawing.

We claim:

The ornamental design for a storage shelf unit, substantially as shown and described.
